W. W. McCALLIP.
FENCE RIVETING MACHINE.

No. 403,950.

Patented May 28, 1889.

UNITED STATES PATENT OFFICE.

WILLIAM WATERMAN McCALLIP, OF COLUMBUS, OHIO.

FENCE-RIVETING MACHINE.

SPECIFICATION forming part of Letters Patent No. 403,950, dated May 28, 1889.

Application filed March 16, 1889. Serial No. 303,585. (No model.)

To all whom it may concern:

Be it known that I, WILLIAM WATERMAN McCALLIP, a citizen of the United States, residing at Columbus, in the county of Franklin and State of Ohio, have invented new and useful Improvements in Riveting-Machines, of which the following is a specification.

My invention relates to improvements in riveting-machines especially adapted for riveting pickets to the rails or bars of an iron fence; and it consists in the peculiar construction and combination of devices, that will be more fully set forth hereinafter, and particularly pointed out in the claims.

15 In the accompanying drawings, Figure 1 is an elevation of a riveting-machine embodying my improvements, showing the manner of using the same. Fig. 2 is a top plan view. Fig. 3 is a cross-section taken on the line $x-x$ 20 of Fig. 2. Fig. 4 is a detail cross-section on the line $y-y$ of Fig. 2.

On a bench or frame, A, which has suitable supporting-legs, B, is bolted a plate, C, having a pair of standards, D, the latter forming the 25 bearings for the pivotal bolt or trunnions E of a beam, F. To one end of the latter is secured a hammer-head, G, with its lower end fashioned as shown in Fig. 3. The front end of the hammer-beam moves between a pair 30 of vertical guides, H H, and suitable mechanism of any well-known kind may be employed for operating the hammer. Such mechanism, however, has not been shown in the drawings, inasmuch as it forms no part of the present 35 invention. In rear of the fulcrum of the hammer-beam and suitably connected with the latter is arranged a coiled spring, the expansive force of which aids the hammer in delivering its blows.

40 On the front end of the frame A is arranged a guide-frame, which comprises a pair of vertical bars, O, having vertical slots P. To the upper ends of the said bars are attached supporting-brackets R, over which the metallic 45 fence bar or rail a is adapted to be moved. Said fence bar or rail is of the usual construction and is rolled with the usual longitudinal groove, b, and is provided with the usual openings, c, arranged at suitable distances apart 50 and adapted to receive the tenoned ends of the rods d.

A pair of guide-bars, S, are secured at regu-

lar distances apart by blocks inserted in their ends, and adjusting-bolts T pass through the ends of said bars and are adapted to move in 55 the slots P. The function of the said bars is to steady and retain the rods d against lateral movement while the same are being riveted in the openings c.

Under the guide-bars S and in vertical 60 alignment with the hammer is a block, U, which has a vertical opening adapted to receive the lower end of the spindle of a die-receiver, V. A set-screw, W, works in a threaded opening in a collar, X, on the upper 65 side of the block and engages the die-receiver, serving to retain the latter at the correct vertical adjustment. The upper end of the die-receiver is dovetailed to receive the transversely-sliding die Y, the latter having an 70 opening or recess, Z, which may be placed a suitable distance out of alignment vertically with the hammer, as indicated in Fig. 1. Said die is retained in place in the die-receiver by a set-screw, A', and may be removed and 75 reversed or replaced by another when desirable.

A horizontal supporting-rail, B', has one end attached to one of the standards O, and has its opposite end supported by a suitable 80 standard, C', and on the said rail travels a grooved wheel, B², from the pivots or axis of which is suspended a carrier-frame, E', the latter being adapted to support one end of the rail a, and hence enable the latter to be 85 easily moved on the bracket R, so that each opening c will successively register with the hammer.

The operation of my invention is as follows: A workman inserts each bar d in succession 90 with its lower end in the die and its upper tenoned end in one of the openings c, thereby arranging the said bar d at an angle other than a right angle to the rail or bar a, as shown in Fig. 1. The hammer is operated, 95 and the same serves to swage the tenoned end of the bar d, and thereby securely fasten the latter to the rail a. The bars d from the center to the ends of the rail a are inclined in opposite directions, as indicated in Fig. 1, and when the said rods d are arranged parallel 100 with each other, which is done when the other fence-rails are placed in position thereon, the bottom rail, a, will become arched, as is ap-

parent, and thereby adapted to withstand a greater vertical strain, and thus prevent the fence-panels from sagging.

Having thus described my invention, I claim—

1. In a machine for riveting iron fences, the combination of the hammer, the die arranged out of vertical alignment therewith, the guide-frame to support one end of the fence bar or rail, and the traveling carrier to support the other end thereof, substantially as described.
2. The combination, in an iron-fence-riveting machine, with the hammer, of the supporting-frame having the arm or bracket R, for the purpose set forth, the guide-bars S, vertically adjustable on said frame, and the die, substantially as described.
3. The combination, with the hammer, of the block U, arranged below the same, the die-receiver supported in the block, and the die fitted adjustably in a recess in the upper end of the receiver, substantially as described.
4. The block U, having the vertical recess and collar X, with set-screw W, the die-receiver having the spindles in said opening or recess and engaged by the set-screw, and the die fitted in the recess in the upper end of the receiver, all in combination, substantially as described.
5. The rail *a* and the bars or rods *d*, with one end secured thereto, said rods being in-

clined from opposite directions from the center to the ends of the rail, whereby the latter will be arched when the bars *d* are parallel, substantially as described.

35

6. The hammer, the die below the same, the supporting-frame having the arm or bracket R, the guide-bars S, secured to the said frame, the horizontal rail B', the grooved wheel adapted to travel on said rail, and the carrier suspended from the axis of said wheel, all in combination, substantially as described.

40

7. The combination, with the anvil having a dovetailed recess, of the slide or die fitting in said recess and having an opening or recess in its upper face, and a fastening-screw, substantially as set forth.

45

8. The combination of the hammer, the anvil having a dovetailed recess, the transversely-adjustable die having a recess in its upper face, and means for suspending and carrying the fence-rail transversely under the hammer and for guiding the pickets, substantially as set forth.

50

In testimony that I claim the foregoing as my own I have hereto affixed my signature in presence of two witnesses.

55

WILLIAM WATERMAN MCCALLIP.
